Primary Examiner — Kendra Leslie Hamilton*Assistant Examiner* — Amanda Christensen(74) *Attorney, Agent, or Firm* — Gerald Hespis; Michael Porco; Matthew Hespis(57) **CLAIM**

The ornamental design for a portion of a charging station, as shown and described.

DESCRIPTION

FIG. 1 is a top, front, right perspective view of a charging station showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a rear, top perspective view thereof.

The broken lines depict portions of the charging station that form no part of the claimed design.

1 Claim, 8 Drawing Sheets(56)
